UNITED STATES PATENT OFFICE.

FREDERICK WENGRAF, OF NEW YORK, N. Y.

AUTOMATIC TENSION DEVICE.

1,247,760.

Specification of Letters Patent. Patented Nov. 27, 1917.

Application filed October 28, 1916. Serial No. 128,200.

To all whom it may concern:

Be it known that I, FREDERICK WENGRAF, a subject of the Emperor of Austria, residing at New York, in the county and State of New York, have made a certain new and useful Invention in Automatic Tension Devices, of which the following is a specification.

This invention relates to automatic tension applying devices.

The object of the invention is to provide a simple, efficient device of the class set forth, which is constructed of few standard parts, and which is economical to manufacture.

A further object of the invention is to provide a simple device which will automatically apply tension to separated parts, and which will automatically maintain the same amount of tension on the parts, regardless of the amount of "give" thereof.

Further objects of the invention will appear more fully hereinafter.

The invention consists substantially in the construction, combination, location, and relative arrangement of parts, all as will be more fully hereinafter set forth, as shown by the accompanying drawing and finally pointed out in the appended claims.

Referring to the drawings:

Figure 1 is a sectional plan view of a structure embodying my invention.

Fig. 2, is a sectional view partly in elevation of the same.

Fig. 3 is a similar view with the tension spring removed.

Fig. 4 is a sectional view taken on the line 4-4 Fig. 1, and looking in the direction of the arrows.

Fig. 5 is a view in elevation of a vehicle tire, and showing one application of the automatic tension device.

Fig. 6 is a sectional view of the non-skid tread employed in accordance with the arrangement shown in Fig. 5.

Fig. 7 is a plan view of the tread shown in Fig. 6.

Fig. 8 is a sectional view taken on the line 8-8 Fig. 6.

Fig. 9 is a sectional view of a modified structure embodying my invention.

The same part is designated by the same reference numerals wherever it occurs throughout the several views.

In accordance with my invention I pro-

vide a casing 9 in which I mount two arms 10, 11, respectively, which project out through the end walls of the casing as shown and one of which is adapted to slide or move lengthwise. The arm 10 is curved or bent 60 while the arm 11 is practically of uniform cross sectional area throughout, so that the surfaces of the arms come in contact with and bear against each other. The bearing or contacting surfaces of the arms 10, 11, are 65 provided with teeth 12, as shown in Fig. 3, and cut in opposite directions to allow the arms to move toward each other, that is, inwardly, toward the center of the casing, but to prevent the arms from moving away 70 from each other, that is, outwardly or out of the casing. Each of the arms 10, 11, is provided with a pin 13, to which is secured a tension spring 14, as shown, which spring acts to draw the respective arms toward 75 each other as will be clearly understood.

Each of the arms 10, 11, is also provided at their respective outer ends outside of the casing 9, with a hook member 15 of any desired form, adapted to engage or be connected with the elements 16 upon which tension is desired to be placed. It is desirable to lock this engagement, and for this purpose, although I am not to be limited in this respect, I provide a well known form of 85 spring clip 17.

To allow adjustment of the tension device, particularly when the device is first applied, I provide a push pin 18, which passes through the wall of the casing 9, 90 and through the stationary arm 11, and which is provided with a flanged head 19 lying in a recess 20 cut in the bearing or contact surface of the arm 11, as shown in Fig. 3. The head 19 of the push pin 18 is rounded, as shown, and bears against the teeth 12 of the arm 10. Thus it will be seen that when the push pin 18 is projected inwardly, by pressure being applied thereto, the arm 10 is forced sidewise so that its 95 teeth are pushed out of contact with the teeth of the arm 11, thereby allowing the arm 10 to be drawn as far out of the casing 9 as the pin 13 thereof will allow. The spring 20, bearing against the arm 10 and 100 the wall of the casing 9, causes the arm 10 to immediately bear against the arm 11 when the pressure against the push pin 18 is withdrawn. The hook members 15 are then secured to the ends, say of the cable 16, to 110

which it is desired to apply tension, and the arm 10 is released. The spring 14 will then draw the arm 10 toward the arm 11, the respective teeth thereof presenting no opposition to this direction of movement, due to their direction of cut, but if additional exterior tension is applied to the member 16, tending to separate the arms 10, 11, the teeth thereof engage with each other 10 and prevent any movement of the arm 10, as is clearly shown.

In Fig. 5, I have shown my device as applied to a non-skid attachment for automobile tires, but it will be understood that 15 my invention, as defined in the claims, is not to be limited to any specific use, as it is obvious that the device may be used in any instance where the slack between elements under tension is desired to be automatically 20 taken up.

In the arrangement shown, the tire 21 is provided with two cables 22, one on each side thereof at its base, on which cables are mounted hook members 23, preferably provided with clip springs 24, as shown. These hook members receive the ends of any desired type of non-skid tread elements, such for instance, as the form designated by reference numeral 26. The automatic tensioning device designated at 29, is attached to the ends of the cables on each side of the tire.

Thus it will be seen that by employing the automatic tension device embodying my invention in connection with any form of 35 non-skid attachment, the slack of the same is automatically taken up, maintaining at all times a tight fit of the parts, thereby eliminating entirely the noise and rattle of loose parts of the non-skid attachments at 40 present employed. Due to the fact that to enable the ready application and removal of the present non-skid attachments, they are made comparatively loose, there has been no effort heretofore to eliminate the noise 45 and rattle caused thereby, but which is obviously objectionable.

While I have shown and described a specific structure embodying my invention, it will be understood that many changes, in 50 detail, will readily occur to those skilled in the art, without departing from the broad scope of my invention, as defined in the claims.

Therefore, what I claim as new and useful, and of my own invention, and desire to secure by Letters Patent, is,—

1. A device for maintaining tension, comprising a housing, a stationary arm and a movable arm located in said housing, means 60 for yieldingly maintaining said arms in contact with each other, means tending to draw said arms longitudinally toward each other, and means for preventing said arms from being drawn longitudinally from each 65 other.

2. A device for maintaining tension, comprising a housing, a stationary arm and a movable arm located in said housing, means for yieldingly maintaining said arms in contact with each other, means tending to draw 70 said arms longitudinally toward each other, and means for preventing said arms from being drawn longitudinally from each other, and means for forcing said arms out of contact with each other.

3. A device for maintaining tension, comprising a housing, a stationary arm and a movable arm located in said housing, means for yieldingly maintaining said arms in contact with each other, the respective contacting surfaces of said arms being provided with oppositely cut teeth, and means tending to draw said arms longitudinally toward each other, said teeth being adapted to permit said movement, but to prevent longitudinal movement of said arms in the opposite direction.

4. A device for maintaining tension, comprising a stationary arm and a movable arm, means for yieldingly maintaining said arms in contact with each other, the respective contacting surfaces of said arms being provided with oppositely cut teeth, a spring connecting said arms to draw said arms longitudinally toward each other, said teeth being adapted to permit said movement, but to prevent longitudinal movement of said arms in the opposite direction.

5. A device for maintaining tension, comprising a stationary arm and a movable arm, means for yieldingly maintaining said arms in contact with each other, the respective contacting surfaces of said arms being provided with oppositely cut teeth, means tending to draw said arms longitudinally toward each other, said teeth being adapted to permit said movement, but to prevent longitudinal movement of said arms in the opposite direction, and hand operated means for forcing said teeth out of engagement to allow longitudinal movement of said movable arm in either direction.

6. In a device of the class described, a casing, a stationary and a movable arm located therein, extending in opposite longitudinal directions, and through the ends of the casing respectively, said arms being in contact with each other and provided with oppositely cut teeth on the opposed surfaces thereof, to allow the inward movement of said movable arm relative to said casing, but to prevent the outward movement thereof, a spring tending to draw said movable arm into said casing, and means for yieldingly holding the teeth of said movable arm in contact with the teeth of said stationary arm.

7. In a device of the class described, a

- casing, a stationary and a movable arm located therein, extending in opposite longitudinal directions, and through the ends of the casing respectively, said arms being in contact with each other and provided with oppositely cut teeth on the opposed surfaces thereof, to allow the inward movement of said movable arm relative to said casing, but to prevent the outward movement thereof, a spring tending to draw said movable arm into said casing, and means for yieldingly holding the teeth of said movable arm in contact with the teeth of said stationary arm.
15. 8. In a device of the class described, arms disposed in longitudinal relation to each other and permanently inclosed within a casing, and one engaging upon the other, said arms being relatively movable longitudinally in one direction, and having means to engage each other to prevent relative longitudinal movement in the other direction.
9. In a device of the class described, arms disposed in longitudinal relation to each other and permanently inclosed within a casing, and one engaging upon the other, and means tending to relatively move said arms longitudinally in one direction, said arms having means to engage each other to
- 5 prevent relative movement in the other direction.
10. In a device of the class described, arms disposed in longitudinal relation to each other and permanently inclosed within a casing, and one engaging upon the other, said arms being relatively movable longitudinally in one direction, and having means to engage each other to prevent relative longitudinal movement in the other direction, in combination with a cable having its ends connected to the outer ends of said arms.
11. In a device of the class described, arms disposed in longitudinal relation to each other and permanently inclosed within a casing, and one engaging upon the other, said arms being relatively movable longitudinally in one direction, and having means to engage each other to prevent relative longitudinal movement in the other direction in combination with a cable having its ends detachably connected to the outer ends of said arms.

In testimony whereof I have hereunto set my hand on this 16th day of October, A. D., 1916.

FREDERICK WENGRAF.
